SUPPORT FOR GUARD RAILS

Judson O. Young, Springfield, Mass.

Application August 3, 1934, Serial No. 738,319

4 Claims. (Cl. 304—36)

This invention relates to a support for guard rails to be used in connection with platforms or stagings supported by ladders or the like. One object of the invention is to provide a support of this character which can be secured to the sides of the ladder independently of the ladder rungs, from which the staging itself is usually supported, and in a manner to afford sufficient strength at the connection to resist the strains which an emergency may throw on the guard rail. In some States safety laws require that the guard rail which is positioned at the outer edge of the platform shall be at a specified height, usually from 30 to 36 inches, above the platform and it is a further object of my invention to provide a support which will meet this requirement whether the platform is positioned closely adjacent the top of the supporting ladders or at a lower elevation, either outwardly or inwardly of the ladders. A further object is the provision of means for attaching the support to the ladder which may be easily adjusted to accommodate ladder sides of different dimensions and which may be adjusted in position lengthwise of the ladder within the space between a given pair of adjacent rungs without removing the support from the ladder.

Other and further objects will be apparent from the following specification and claims.

In the accompanying drawing,

Fig. 1 is a general diagrammatic view of a staging including the guard rail support of this invention;

Fig. 2 is a side view of the device illustrating one operative position;

Fig. 3 is a similar view illustrating a different operative position; and

Fig. 4 is a plan view of the device.

Referring to Fig. 1, which shows in general the manner in which the device is used, 10 designates spaced ladders which support a staging or platform 11 by means of conventional brackets or jacks 12 which engage the rungs 13 of the ladder. The guard rail is shown at 13 and the guard rail supports are generally indicated at 14.

Referring to Figs. 2, 3 and 4, the guard rail support is shown as comprising two flat metal strips 15 and 16 each curved at one end in the plane of the strip as indicated at 17 and 18. Strip 15 is provided at the opposite end with a loop 20 to receive the guard rail and the two strips are riveted or otherwise secured together 55 adjacent loop 20 as indicated at 21. A second

guard rail loop 22 is riveted or otherwise secured to strip 15 a short distance inwardly of the curved end of said strip, and in a position to extend downwardly when the support is in position. The curved ends of the strips 15 and 16 are adapted to be spread apart to receive one of the side members 19 of the ladder between them as shown in the drawing, and the ends of the curved portions are provided with apertures 23 through which a bolt 24 provided with a wing nut 25 is inserted. The apertures 23 and 28, later described, are preferably square and the bolts used are of the carriage bolt type having a squared portion adjacent the head engaging in the squared openings to prevent turning of the bolts when the wing nuts are applied. A block 26, which may conveniently take the form of a piece of channel iron as shown, is pivoted on bolt 24 with its closed face positioned to engage a face of the ladder side member 19. A plurality of apertures 28 are formed in the strips 15 and 16 inwardly of the apertures 23 and are adapted to selectively receive a bolt 29, provided with a wing nut 30, on which is pivoted a block 31 similar in form to block 26. By properly selecting the holes 28 through which to insert bolt 29 ladders having side members 19 of various depth dimensions may be accommodated in an obvious manner, the width of the side member being accommodated by the spring of the strips and varying the position of the wing nuts on the bolts 24 and 29. As will be clear, the weight of the projecting portion of the support and the guard rail 13 tend to clamp the blocks and support to the member 19 and this clamping action is increased when any additional weight such as that of a workman is thrown on the guard rail in case of emergency. The blocks 26 and 31 are made of sufficient length to distribute the forces placed upon them over a sufficient surface of the member 19 to support the maximum emergency load they will be called on to bear.

The curvature of the strips 15 and 16 permits the supports to be positioned closely adjacent the top of the ladders, as shown in Fig. 2, and still position the guard rail 13, which is placed in loops 20, a distance "a" above the platform 11 to meet the prescribed requirements. The distance "a" may be varied within the distance between ladder rungs by merely raising the free end of the support to relieve the clamping action of the blocks and then sliding the support to the desired position, or for smaller adjustments by selection of an aperture 28 permitting a greater

downward swing of the support before the blocks engage the sides of the ladder. The curvature of the strips at 17 and 18 will be made such as to give the maximum desired elevation when the 5 bolt 29 is in the aperture 28 nearest aperture 23.

In Fig. 3 is shown the position of the parts when the platform 11 is supported inwardly of or beneath the ladder. In this case the supports are secured to the members 19 as before but the 10 guard rail 13 is placed in loops 22 instead of loops 20 and the support adjusted on the member 19 to secure the desired vertical distance "a" between the platform and the rail.

The supports are applied to and removed from 15 the ladder side by the temporary removal of bolt 24 and block 26, in an obvious manner. To promote convenience in handling the device, block 26 is preferably secured to the support by means of a chain 35.

20 As will be clear from the above description, the guard rail support is carried entirely by the side of the ladder and failure of the rungs of the ladder which support the staging will not affect the strength or stability of the guard rail. 25 Furthermore by curving the support and placing the second guard rail loop on the under side, the support may be placed closely adjacent the top of the ladder even when the latter is placed beneath a projecting roof, as shown in dotted 30 lines in Fig. 2, and yet position the guard rail the necessary distance above the staging platform.

I claim:

35 1. A device of the character described which comprises an elongated member provided at one end with means for receiving a guard rail, means at the opposite end for releasably clamping the device to the side member of a ladder, the last named end of the elongated member being curved 40 to position the rail supporting end substantially above the point of attachment to the ladder, and a second guard receiving means secured to the device adjacent the clamping means.

45 2. A device of the character described which comprises an elongated member provided at one end with means for supporting a guard rail, spaced

fork members formed at the opposite end to receive a side member of a ladder between them, and two blocks pivoted between the fork members in position to engage opposite faces of the side member of the ladder, said forked members being curved to position the guard rail supporting end of the elongated member substantially higher than the blocks when the latter are in clamping engagement with the faces of the side of the ladder. 80

3. A device of the character described which comprises an elongated member provided at one end with a loop to receive a guard rail, spaced fork members formed at the opposite end to receive a side member of a ladder between them, two blocks pivoted between the fork members in position to engage opposite faces of the side member of the ladder, one of said blocks being adjustable toward and from the other, said fork members being curved to position the guard rail supporting end of the elongated member substantially higher than the blocks when the latter are in clamping engagement with the faces of the side of the ladder, and a second guard rail receiving loop secured to the under side of the elongated member adjacent its forked end. 85 90 95

4. A device of the character described which comprises two elongated flat metal members, one of said members being provided at one end with a loop to receive a guard rail, the second member being secured in face to face relation to the first member adjacent said loop, the free ends of said strip being spread apart to engage opposite side faces of a side member of a ladder, two blocks pivoted between the strips in position to respectively engage the front and rear faces 110 of the side member of the ladder under the weight of the strips, one of said blocks being adjustable toward and from the other, said free ends of the strips being curved to offset said blocks and position said guard rail receiving loop substantially 115 higher than the blocks when the latter are in clamping engagement with the side member of the ladder, and a second downwardly extending guard rail receiving loop secured to one of the strips adjacent its ladder engaging end. 120
